1,930,946

DRIVING AND CONTROLLING MECHANISM
FOR POSTAL MACHINES

Ralph G. Whitlock, Los Angeles, Calif., assignor,
by mesne assignments, to National Postal
Meter Company, a corporation of California

Original application May 17, 1926, Serial No.
109,643. Divided and this application January
26, 1929. Serial No. 335,331

2 Claims. (Cl. 192—125)

This application is a division of an application entitled Machines for sealing and to print indicia on letters, filed by me on May 17, 1926, Serial Number 109,643 and relates particularly to a means, controllable by letters (mail pieces), carried on a conveyor, forming part of the sealing mechanism, for automatically stopping and starting, alternately, the sealing and indicia printing means whereby to provide "rest" intervals for 10 the mail pieces for the printing operations.

And further relates to the construction of a mechanism of simple, durable and economic construction for the efficient and dependable intermittent operation of various parts of machines, 15 more particularly postal machines.

An object of my invention is to provide simple means for causing a single source of power to alternately and intermittently actuate functionally distinct mechanisms of an organized machine.

To the above purposes my invention consists in the novel construction, arrangement and combination of parts, as hereinafter fully, clearly and concisely described, definitely pointed out in 25 my claims and illustrated by the accompanying drawings (4 sheets) in which—

Fig. 1 is a front elevation of a postal machine equipped with an intermittent drive mechanism constructed in accordance with my invention.

30 Fig. 2 is a diagrammatical elevation showing the relative gear and clutch relation.

Fig. 3 is an end view of a portion of the drive mechanism showing the gear relation and control of the secondary clutch.

35 Fig. 4 is a sectional view of a portion of the clutch showing the clutch pin.

Fig. 5 is a more or less diagrammatical side elevation similar to Fig. 2 showing the gear train and gear shift of the drum drive.

40 Fig. 6 is a more or less diagrammatical side elevation similar to Fig. 2 showing the gear train and gear shift of the drum drive.

Fig. 7 is a more or less diagrammatical side elevation similar to Fig. 2 showing the trip mechanism from the letter trip to the clutch.

Fig. 8 is a more or less diagrammatical front elevation of the trip mechanism shown in Figs. 1, 2, 7 and 9, in normal position, with a second position indicated in broken lines.

50 Fig. 9 is a more or less diagrammatical plan view of the trip mechanism shown in Figs. 1, 2, 7, 8 and 9, in normal position, with a second position shown in broken lines.

Fig. 10 is a more or less diagrammatical view 55 of a portion of the trip mechanism residing adja-

cent the clutch similar to Fig. 3 with the parts in the same operative position.

Fig. 11 is a view similar to Fig. 10, showing the same parts in a second operative position.

The reference numerals used in the drawings 60 are the same as those used in my application, Ser. No. 109,643, filed May 17, 1926. In the drawings, A designates a frame or stand; F a hopper and envelope feeding means; D a printing press; 19 a motor; 87 a feed drum; 94 a sealing drum; 65 130 a conveyor; 133 a moistener, all of which are, or may be, of known construction and except in combination form no part of my invention.

The frame 22 has a cross member 16 upon which is mounted the motor 19 which by means of 70 belt 34 conveys power and motion to the pulley 39 keyed on shaft 32.

Keyed to shaft 32 is gear wheel 33, which engages with and actuates gear wheel 36, rotatably mounted on shaft 38. Keyed to shaft 38 is clutch 75 member 47 having a clutch pin 44 slidably mounted in cavity 45 therein, tensioned by spring 49 for engagement with a corresponding cavity 41 in gear wheel 36, and provided with a head 46, under the shoulder of which, wedge 52 engages to remove the said pin 44 from cavity 41 in gear wheel 36, said spring 49 operating between shoulder 47 of pin 44 and a retaining plate 48, in clutch member 47.

Shaft 38 has rotatably mounted on it adjacent 85 to clutch member 47, a spring tensioned clutch control member 53 carrying the said wedge 52, and is actuated by bar 155 having its lower end shaped and disposed to receive contact from a trip device 90 arm 153.

Shaft 32 has key mounted on it a cam 147, positioned for a lifting engagement with the arm 153 at a point adjacent to the bottom of the said bar 155.

The recited gear wheel 33 also meshes with and 95 actuates gear wheel 40 which is secured to secondary clutch element 162, rotatably mounted on shaft 35, and which is engaged by the opposed section of the same clutch, which may be of any conventional design having a clutch collar 161 100 slidably keyed to shaft 35 to be engaged by the corresponding section of actuating arm 160 which is connected to bell crank 159, and operated by lever 158, supported on frame 22, and having at its upper end roller 157 which rides on the cam 105 surface 42 of clutch element 47. Dwell 156 is provided in clutch element 47 to actuate lever 158 and its connections to operate secondary clutch element 161.

Shaft 35 has key mounted on it bevel gear 72 110

which meshes with bevel gear 74 key mounted on shaft 73 which has key mounted on it bevel gear 75 for mesh with bevel gear 76 key mounted on shaft 77, which shaft also has key mounted on it 5 gears 78 and 79 which form a gear shift mechanism together with gears 82 and 83 on shaft 80 and gear 84 on shaft 81 and gear train 85, 170 and 172 which drive the recited drums 87 and 94, and the feed roller 168 by gear 169 through shaft 173, 10 which same are all supported in frame 90, and the conveyor belt 130 is driven by drum 94.

The gears are shifted thru the lateral movement of shaft 80 by any conventional means, not shown, for speed variation of the feed and conveyor 15 system.

The trip arm 153 is spring tensioned, and mounted as at 154 so as to be universally movable relative to frame 59 and is actuated, through a compound lever action of arms 152, 149 and 150 20 fulcrumed as at 151, when trip 148, which is normally in the path of mail pieces being moved by conveyor belt 130, is moved thru contact with a mail piece, as shown by the dotted lines in Figs. 8 and 9.

Upon the arrival of a piece of mail matter, being conveyed by the belt 130, at a point to contact trip 148, and it being actuated, the connected arms 149 move trip arm 153 laterally into the path of continuously rotating cam 147, which raises trip 25 arm 153 to contact and raise bar 155 which rotates clutch control member 53, moving wedge 52 out from under the head 46 of clutch pin 44 allowing it to spring engage in cavity 41 in continuously rotating gear wheel 36, and upon this 30 engagement, the clutch member 47 and its keyed shaft 38 are rotated to operate any mechanism attached thereto, such as a postal press. In the present device, rotation of shaft 38 is adapted to operate the press 128, the details of the mechanical 35 operating connections between shaft 38 and the press operating machine D not being shown here. The rotation of clutch member 47 moves lever 158 out of dwell 156 and thereby operates secondary clutch member 161 to disengage and thus stop 40 the driving mechanism connected thereto, namely gears 72, 74, 75, 76 and the other shafts, gears, drums, conveyor, etc., actuated by them, thus bringing the envelope that engaged and actuated trip lever 148 to a stationary position, or rest, at 45 the press 128 to receive indicia as actuated and operated by clutch 47 and shaft 38.

Trip arm 153 is returned to original position by spring tension of spring 153a upon release of the cam contact, which occurs at the next revolution 50 of cam 147, which consequently actuates the connected members 152 and 149, 150 and 148, these members being returned to their normal position by spring 149a shown in Fig. 8.

60

65

70

75

Trip arm 153 when raised moves trip 148 above the plane of a mail piece by means of arm 149, and the recited return movement of arm 153 moves trip 148 to its original position as shown in Figs. 1, 2, 8 and 9 and the spring tension replaces it to a plane to interrupt following mail pieces upon the passage past that point of the one last actuating it. This removal of arm 153 instantly after being raised by cam 147 to actuate bar 155 allows bar 155 to drop, under the spring tension, to its original position and thus rotate clutch member 53 in a reverse direction to place wedge 52 at its original position to intercept and pull out the head 46 of pin 44, at the same point in, and on the completion of each cycle of its operation, and by the withdrawal of pin 44 from the cavity 41 in gear wheel 36 the actuation of the clutch 47 and its keyed shaft 38 ceases, and at the same time the dwell 156 through the same cycle of rotation is brought to a position to receive 95 the roller 157 of secondary clutch arm 158 which causes the secondary clutch member 161 to engage, thereby actuating the driving mechanism operating the feed drums and conveyor.

Thus my invention provides a simple and efficient means to intermittently and alternately actuate and operate a feeding mechanism and a printing mechanism in a postal machine.

The form of the device illustrated and described herein is submitted in accordance with statutory 105 requirement by way of exhibiting one form of embodiment of my invention. Various changes, alterations or modifications of the structure may be made without departure from my invention as defined in the following claims.

I claim:

1. In combination: a single revolution clutch, a bar for actuating said clutch; a cam positioned adjacent to said bar; an arm adapted to be positioned relative to said cam and said bar to transmit power from said cam to actuate said bar and throw in said clutch; and automatic means for moving said arm out of said position after said bar has been actuated to start a revolution of said clutch to permit said bar to return to its 110 original position and cause said clutch to stop at the end of its revolution.

2. A combination as in claim 1 including a trip adapted to be disposed adjacent the surface of a conveyer for engagement with an article thereon, 125 said trip being connected to said arm and being adapted to actuate said arm when engaged by an article and moved therewith; and means on which said trip is mounted to remove said trip from the path of an article which has contacted 130 and operated said trip.

RALPH G. WHITLOCK.
